UNITED STATES PATENT OFFICE.

GEORGE J. HAGAN, OF PITTSBURGH, PENNSYLVANIA, ASSIGNOR TO DARWIN S. WOLCOTT, TRUSTEE, OF SEWICKLEY, PENNSYLVANIA.

STOKING MECHANISM.

Application filed August 13, 1918. Serial No. 249,672.

To all whom it may concern:

Be it known that I, GEORGE J. HAGAN, residing at Pittsburgh, in the county of Allegheny and State of Pennsylvania, a citizen of the United States, have invented or discovered certain new and useful Improvements in Stoking Mechanism, of which improvements the following is a specification.

10 The invention described herein relates to certain improvements in stoking mechanism especially applicable to that class or kind embodying a central retort with fuel supporting members extending with a downward inclination from opposite edges of the retort. While some of the improvements claimed herein are as stated applicable generally to the type stated, other improvements are specially applicable to such 15 stokers as employ a screw feed for forcing the coal into the central retort.

In the accompanying drawings forming a part of this specification Fig. 1 is a front elevation of a boiler having combined therewith a stoking mechanism embodying the improvements claimed herein; Fig. 2 is a sectional plan view, the plane of section being indicated by the line II—II, Fig. 1; Fig. 3 is a sectional elevation, the plane of section being indicated by the line III—III, Fig. 2; Fig. 3^a is a sectional view on a plane indicated by the line III^a—III^a, Fig. 1, of the mechanism for operating the fuel feed, grate bars, etc.; Fig. 4 is a view partly in side elevation and partly in section of the mechanism for operating the grate bars and ash plate; Fig. 5 is a top plan view partly in section of a portion of the fuel supporting members; Fig. 6 shows in elevation one 40 of the sections of a hollow grate bar; Fig. 7 shows in side elevation an auxiliary bar in position alongside of a main bar; Fig. 8 is a transverse section on a plane indicated by the line VIII—VIII, Fig. 5; Fig. 9 is 45 an end elevation of a main or hollow bar; Fig. 10 is a transverse section of the same; Fig. 11 shows side and end views of a filling piece; Fig. 12 shows in side elevation and partial section the manner of connecting 50 the link 16 to the operating arms and Fig. 13 is a detail showing the valve controlling the flow of air to the distributing chamber.

In the practice of the invention fuel is fed from the hopper 1 into the central re-

tort passage by means of a screw 2, the screw being adapted to be rotated in any suitable known form of mechanism indicated at 3. On the shaft of the screw is secured a cam 4 which is adapted to engage pins 5 on the reciprocating member 6. This member is slotted as shown in Fig. 1 to permit of the movement of the member 6 transversely of the shaft, such movement being effected by the engagement of the cam 4 with the pins 5 on the reciprocating member. This member is provided with diametrically arranged extensions 7 which have their outer ends connected to arms 8 on shafts 9 arranged on opposite sides of the fuel supporting means. On these shafts 9 are secured at points adjacent to the front ends of the boiler, arms 11 which are connected by links 12 to arms 14 on the shafts 15. The upper ends of the arms 14 are adjustably connected to links 16 which are adapted to be detachably connected to pins 17 on arms 18 keyed to the shafts 19. These shafts 19 are provided with toothed sectors 20 adapted to engage teeth formed on the edges of the web portion 21 of the movable grate bars 22 T-shaped in cross-section as shown in Figs. 5 and 8. The shafts 15 are also provided with arms 23 having their outer ends pivotally connected to the ash plates 24 as clearly shown in Fig. 3. These ash plates have their outer edges supported on arms 25 secured to the shafts 26 which are adapted to be rotated to change the angular position of the dump plates by means of worms 27 engaging toothed sectors 28 secured to the shafts 26 outside of the furnace. In order to vary the movement of the movable grate bars 22, the connections between the links 16 and the arms 14 are formed by blocks 29 adjustably arranged within slots 30 in the ends of these links.

The mechanism described affords means for imparting from the shaft of the screw 100 for feeding coal into the furnace a reciprocation of the movable grate bars to effect a progressive movement of the fuel as it is fed onto the inner ends of the grate bars along the latter and also to the ash plate 105 to effect the movement of the ashes across the dump plate into the ash pit.

The main grate bars 31 are made hollow as clearly shown in Figs. 3, 5, 8, 9, it being preferred that such bars should be 110

made in two longitudinal sections which are held together to form a unit by means of suitable transverse bolts as shown in Fig. 5. Suitable ports 32 and 33 are formed adjacent to the inner and outer ends respectively of the hollow bars for the passage of air into and from the bars as hereinafter described. The front or inner ends of the bars adjacent to the retort are supported upon removable nozzles or hollow blocks 34 which in turn rest upon the upper edges of the retort and the side walls of the chambers exterior to the retort and the rear ends of the bars are supported in seats formed in the upper ends of the walls 36 forming the outer walls of air chambers on opposite sides of the median plane of the stoking mechanism. In order to hold the front ends of the bars 31 from lifting away from their supporting blocks, hooks 37 are formed on the undersides of the bars, said hooks being adapted to extend down into the nozzle blocks 34 and engage projections 38 on the inner walls of the nozzle blocks as shown in Fig. 3. The hooks are held in engagement with such projections 38 by means of beveled projections on the rear or outer ends of the bars fitting inside of the seats of the upper ends of the walls 36. As it will be seen by reference to Figs. 2, 3, 5 and 8, the auxiliary or T-shaped bars 22 rest upon adjacent main bars 31, the webs 21 of the auxiliary bars extending down between adjacent main bars 31. In order to provide recesses for the passage of the webs 21 the outer faces of the main bars 31 are provided with laterally projecting shoulders 40 and 41 at their front or inner ends and with shoulders 42 at their rear or outer ends, the respective shoulders on one of the main bars bearing against corresponding shoulders on the next adjacent bars when in position in the furnace. In some cases it may be desired to provide means for breaking up the mass of coal in the retort which can be conveniently effected by forming on the webs 21 of the auxiliary bars, fingers 43 adapted on the forward reciprocation of the auxiliary bars to project into the retort. When this construction is used, the shoulders 40 and 41 are spaced a distance apart to form recesses for the guidance of these fingers 43 as clearly shown in Figs. 5 and 7. It will be understood that the thickness of the shoulders 40, 41 and 42 and the webs of the T-shaped bars are so proportioned that ample spaces will be left between the webs of the T-shaped bars and the sides of the recesses into which the webs project for the flow of air into the fuel as herein-after described.

In practice it is desired that all the bars should be similarly constructed so as to avoid difficulty in replacement and hence

provision should be made for filling up the spaces occupied by the webs 21 and the fingers 43 on the sides of the bars next adjacent to the walls of the furnace. To this end filling pieces 44 shaped to fit within the recessed sides of the main bar and to project in between the spaced shoulders 40 and 41 are secured to the walls of the furnace or may be wholly supported by the main bars. In the construction illustrated in Fig. 3, an air chamber is formed below the grate surfaces by the side walls 36 and this chamber is subdivided by a brick wall and the outer walls 35 of a chamber 46 enclosing the central retort. The chamber 46 formed by the side of the retort and the walls 35 is external of the retort and spaced therefrom, so as to form such chamber or passage for air. Air is admitted through central flue 45 but is prevented by a wall 46 from flowing up around the retort into the front ends of the hollow bars and hence passed directly into the two main or receiving or supply chambers under the grate surfaces. From these chambers the air enters the rear or outer ends of the hollow grate bars through the ports 33 and flows along the same to the ports 32 at their front or inner ends from whence it flows into the air passages 46 on opposite sides of the central retort. From these passages the heated air will flow through ports 47, the flow of air through the ports being controlled by valves 48, into the distributing boxes 49 arranged immediately under the grate surfaces. From these boxes the air flows up between adjacent main and auxiliary bars and is distributed laterally by the auxiliary bars 22 which have their under surfaces grooved as shown in Figs. 7 and 8 for the flow of air into the fuel. Openings 50 are made through the ends of the hollow bars for the flow of heated air into the fuel within the retort. While these openings may be made in any suitable manner, it is preferred that they should be made by notches formed in the end walls of the sections of the bars 31, the notches being so arranged in one section as to alternate with corresponding notches in the complementary section.

It will be observed that the supply chambers are separated from the ash plate by the walls 36 so that air entering the fuel will flow first to the closed supply chambers and along the passages in the bars to the front ends of the latter where the air-flow divides, part escaping through the perforations 50 into the fuel and part flowing through chambers 46 into the distributing boxes and up between the grate bars into the fuel. While it is believed that sufficient air for combustion of the fuel will be supplied through the passages in the

grate bars, additional quantities of air can be supplied to the fuel by opening the valve 51 thereby permitting the air to flow from the supply chambers directly into the distributing boxes. It is characteristic of the improvement described and claimed herein that as the supply chambers are closed, air can escape normally therefrom only through the passages in the grate bars thus insuring a preheating of the air entering the fuel bed or combustion chamber.

I claim herein as my invention:

1. A stoking mechanism having in combination a central retort, fuel supporting members extending from opposite sides of the retort and at an angle to the axis of the retort, movable ash supporting plates adjacent to the ends of the fuel supporting means for the reception of ashes, a screw for feeding fuel to the retort and means operative by the screw shaft for shifting the ash plate relative to the fuel supporting members to effect a movement of the ashes across the ash plate.
2. A stoking mechanism having in combination a central retort, fuel supporting

means extending from opposite sides of the retort and at an angle to the axis of the retort and consisting of members movable relative to other members, movable ash supporting plates arranged at the ends of the respective fuel supporting means for the reception of ashes, a screw for feeding fuel into the retort and means for operating the screw and shifting the movable fuel supporting members and the ash plate relative to the fuel supporting members.

3. A stoking mechanism having in combination a retort, fuel supporting means extending from the retort at an angle to the direction of movement of fuel in the retort, a movable ash supporting plate adjacent to the outer ends of the fuel supporting means for the reception of ashes, a screw for feeding fuel into the retort and means for rotating the screw and reciprocating the ash plate relative to the fuel support to advance ashes across the ash plate.

In testimony whereof, I have hereunto set my hand.

GEORGE J. HAGAN.
